UNITED STATES PATENT OFFICE.

CHARLES F. LITTLEJOHN, OF NEW HAVEN, CONNECTICUT, ASSIGNOR, BY MESNE ASSIGNMENTS, TO THE RECORDING REGISTER & FARE BOX COMPANY, OF NEW HAVEN, CONNECTICUT, A CORPORATION OF CONNECTICUT.

RECORDING FARE-REGISTER.

1,093,059.

Specification of Letters Patent. Patented Apr. 14, 1914.

Application filed January 26, 1906. Serial No. 297,997.

To all whom it may concern:

Be it known that I, CHARLES F. LITTLEJOHN, a citizen of the United States, and resident of New Haven, in the county of 5 New Haven and State of Connecticut, have invented certain new and useful Improvements in Recording Fare-Registers, of which the following is a full, clear, and exact specification.

10 This invention is an improved registering and recording machine, and although in many respects applicable to other purposes, it is herein shown in an embodiment suited for the registering and recording of the 15 fares taken on street car, ferry or other passenger lines.

The general object of the invention is to provide a machine of this class, of simple construction and positiveness of action, combined with security against derangement or 20 error due to either ignorant or fraudulent manipulation.

Figure 1 of the drawings is a front elevation of this machine, with the front cover 25 removed, a portion of the recording mechanism being also shown in section. Fig. 2 is a rear elevation, with the back plate of the case removed. Fig. 3 is a front elevation, the upper portion showing a part of the 30 front plate or dial cover, while the lower portion is shown in section taken on the line 3 of Fig. 5. Fig. 4 is an end elevation in section taken on the line 4—4 of Fig. 2. Fig. 5 is an end elevation of the opposite 35 end of the register in section taken substantially along the line 5—5 of Fig. 1. Fig. 6 is a plan view of a portion of the recording 40 mechanism, the end wall of the casing and a few of the parts being shown in cross section. Fig. 7 is an end elevation projected from Fig. 6, in section taken on the line 7—8 of Fig. 6, showing the recording and direction indicating mechanisms in one position, while Fig. 8 is a similar view showing 45 the said mechanisms in a different position. Fig. 9 is an end elevation of one of the registering dial ratchets, and its associated stop and resetting devices. Fig. 10 is a rear view of a portion of Fig. 9, projected therefrom, while Fig. 11 is a front 50 view of the ratchet wheel, also projected

from Fig. 9. Fig. 12 is a view somewhat similar to that of Fig. 9, but showing two dials one of which is in its stopped or zero position. Fig. 13 is a front view projected 55 from Fig. 12, showing the two dial wheels, and the respective positions of their resetting pawls. Fig. 14 is a view similar to that of Fig. 12, showing the position of the zero stop and interlocking devices, when all the 60 dials are at their zero positions. Fig. 15 is a fragmentary end view somewhat similar to that of Fig. 12, illustrating one of the phases of operation of the units ratchet and its stop pawl. Figs. 16 to 19 inclusive 65 are end elevations illustrating the operation of the full stroke and bell hammer mechanisms. Fig. 16 represents the registering arm and full stroke mechanism at the beginning of their movement. Fig. 17 represents the same mechanism at a later stage 70 of movement. Fig. 18 shows the position of the devices at the beginning of the return movement of the registering arm, and Fig. 19 shows the parts at the end of the return 75 movement of the registering arm. Fig. 20 is a plan view; Fig. 21 an end view of the totalizer; and Figs. 22 and 23 are detail views of the register locking mechanism and the actuating cam therefor. 80

The register shown and described therein is of the general type shown in U. S. Patent #567,315 of Sept. 8, 1896. Therefore only a brief description need be given of those parts of the present machine which are substantially similar to those described in the 85 said patent.

The mechanism is contained in a casing 20, provided with a front plate 21, and a back plate (not herein shown). The bell 90 22 is supported in an auxiliary case 23, which is attached to the main case, the bell hammer 24 being provided with a journal which extends through a hub in the casing 20 through the interior thereof, and has 95 fixed upon its inner end a bell arm 25 which is operated to retract the bell hammer, the latter when released being swung sharply against the bell by means of the spring 26. The front plate 21 is provided with glazed 100 apertures through which appear a single figure of each of the trip registering dials

28, 29 and 30, representing the units, tens and hundreds, respectively, of the numerical registrations of the respective trips. The direction indicating dial 51 also shows 5 through a glazed opening in the front plate, the dial being movable to different positions to represent different trip directions or zones, or other divisions of the route, or of time, which it may be desired to register 10 and record separately. The trip registering dials 28, 29 and 30 are appurtenant to or integral with the ratchet wheels 34, 35 and 36, respectively; and these dials are connected with the recording wheels 40, 41 and 42, respectively, by means of the sleeves 43 and 44 and the shaft 45, respectively, these 15 wheels being provided with suitable type 46, each type wheel being provided with a series of numeral type from 0 to 9, corresponding to the visible numerals 47 on the 20 face of the registering dials.

The impressing type are so disposed with relation to the dial numerals as to bring the type to the recording position indicated by 25 the dot-and-dash line 3 in Fig. 5, when the corresponding dial numerals show through the glazed openings, which is herein designated their indicating position, occupied by the zero numerals 47 in Fig. 3. The position 30 designated by the line 3 is herein termed "the recording position", because it is at this position that the type corresponding with the numerals appearing at the indicating position, are impressed against the 35 record strip. Similarly the direction or zone visibly indicated upon the front of the register is also recorded upon the record strip by means of impressing type 49 and 50, which are also at the recording positions indicated by the line 3 in Fig. 5 when the corresponding directions or zones are shown through the glazed openings, at the indicating 40 position of the direction dial.

The direction dial 51 is mounted upon a 45 direction arm 52 which is supported upon a bearing or bushing 53, the impressing type being appurtenant to the hub of the direction arm, or being inserted therein as shown in Fig. 3.

50 The trip register dials 28, 29 and 30 are advanced in proper consecutive order, one unit at each actuation of the register by means of the registering pawls 55, 56 and 57, pivotally mounted at 58 upon the registering 55 arm 59, which is mounted concentrically with, and at opposite ends of the dials, the pawl carrying portion of the arm arching over the dials, as best shown in Fig. 1. The left hand journal of the arm 59 extends out 60 through a bearing in the end wall of the case 20, and is provided, externally to the casing, with a registering lever 60, which may be engaged by or connected with any suitable actuating apparatus on the car or other ve-

hicle on which it may be used, so as to swing 65 the arm forward and back, which has the effect of advancing the dials by a step by step movement, one unit at each actuation. Suitable detents 62 are also provided for engaging with the ratchets to prevent return 70 movement of the dials.

The parts thus far described are in construction, function, and mode of operation, substantially like the corresponding parts of the register shown and described in the 75 aforesaid U. S. Patent #567,315, to which reference may be had for a more detailed description, if desired.

I will now describe more in detail the features which constitute the present invention:—

In this machine, as in the machine of the aforesaid patent, interlocking means are provided between the different departments of the machine, so as to prevent the concurrent 85 operation of two or more departments, and to prevent the successive operations of the several departments otherwise than in their proper sequence. The principal departments of the machine are for convenience 90 herein designated in a general way as the registering mechanism, the direction or zone indicating mechanism, the recording mechanism, and the resetting mechanism; and it is important that no two of these departments 95 be operated concurrently.

The registering mechanism includes the bell mechanism, and the totalizer or total register mechanism. The trip register dials show the number of fares registered in each 100 trip or zone, and are reset to their zero positions, at the end of each trip or zone, whereas, the totalizer or total register comprises a train of dials which go on continuously, registering the successive fares concurrently 105 with the trip register but continuing on without being reset to zero, and thereby adding together the entire registration, so as to show the total number of fares registered during a given period. The proper sequence 110 of operation of these departments of this machine is as follows:—First, the registering mechanism, the direction indicating, the recording, and the resetting mechanisms being locked out of operation. Next, the recording mechanism, the first movement of which serves to lock the registering mechanism out of operation. At or near the completion of the recording operation, the direction indicating mechanism is released and 115 operated and the resetting mechanism is released ready for operation, the recording mechanism itself being locked at the conclusion of its operation to prevent repetition 120 of its operation until the trip register shall have been set to zero. Next, the resetting operation which serves to move the trip register 125 dials to zero. At the conclusion of the

resetting operation, the interlocking devices, which up to this time have remained locked to prevent them from being thrown off, are released, and are then moved back 5 to their initial position, locking the resetting mechanism out of operation, but releasing the registering devices.

In order to increase the certainty and security of those portions of the interlocking devices which hold the registering mechanism out of operation, while the recording and resetting mechanisms are being operated, I have provided a locking member 70, which is pivotally mounted at 71, and engages 10 with the other interlocking devices so as to project the upper end of the locking member outwardly through the case into the path of movement of the registering arm 60, as indicated by the dot-and-dash line 72, 15 thereby locking the registering mechanism out of operation, externally to the case. The lower end of the member 70 is forked so as to straddle the arm 74, as shown in Figs. 2 and 4. The fork opening is inclined so that 20 as the arm 74 drops when released during the recording operation, the upper end of the locking member 70 is carried outwardly; and when the arm 74 is raised after the completion of the resetting operation, the 25 locking member 70 is retracted to the position shown in Fig. 2, thereby releasing the registering arm 60. In the machine of U. S. Patent #567,315, the registering mechanism is locked out of operation only by means of 30 the internal latch 95^a, which is swung in front of the arm 45^a, appurtenant to the registering arm 43. It has, however, been found possible in actual practice to break 35 the registering arm 43, or its connections 40 with the registering lever 42 of the patent by a sufficiently hard pull upon the operating cord or lever. In the present instance, the locking member 70 is interposed directly 45 in front of the registering arm 60, which is the prime mover of the registering train, and when thus locked no breaking strain 50 can be transmitted to the inner parts of the register.

The arm 74 is herein shown to be appurtenant 55 to that section of the interlocking mechanism which operates between the recording and the resetting mechanism, this being in the present instance mainly for convenience of construction. That mechanism 60 is released and therefore operates the arm a little after the preliminary movement of the recording mechanism; but before the actual printing stage of that operation is reached. Therefore the registering lever 60 is locked 65 by the locking member 70 during the actual or effective part of the recording operation; and remains locked until the dials have been reset to zero and the interlocking devices 70 have been restored to the position shown in

Figs. 2, 4, and 5, to permit the subsequent 65 registering operations. For additional security and in order to lock the registering devices out of operation from the very commencement of the recording operation, the registering mechanism is provided with an 70 arm 76 substantially like the arm 45^a of the aforesaid Patent 567,315, which is engaged by a latch 77 operative with the recording mechanism in the manner shown and described in the said patent, and which therefore need not 75 be further described herein. At the very beginning of the recording operation the latch 77 is swung beneath the arm 76. But when the registering mechanism is locked at this point only it has been found possible, as 80 stated in the introductory description of this device, to apply pressure enough to the prime moving lever 60 to break some of the parts intermediate that lever and the arm 76, hence the desirability of adding the locking arm 70, acting directly upon the prime moving lever itself, and thus avoiding the transmission of breaking strains to or through the interior mechanism. This type 85 of register, like many others, is provided with a totalizer or total register which is best shown in Figs. 2, 20 and 21. Only the first dial of the totalizer registering train is shown in Fig. 20, these dials being positively 90 geared together in any of several well-known ways; but the first or units dial of the train, which is herein more particularly shown, is commonly advanced by means of a ratchet wheel and pawl, no provision being 95 made for preventing the overrunning of this dial either by its rapid use or by malicious design, so as to carry the indications of the total register out of conformity with those of the trip register. In the present invention 100 means are provided for interlocking the total register with the trip register so as to prevent them from being moved otherwise than in conformity with each other, during the registering operations, and the means 105 for doing this will now be described:— 110

The ratchet wheel 80 which is appurtenant to the units dial 81 of the total register is provided with the customary ratchet teeth upon its periphery, which teeth are engaged by the advancing pawl 82 appurtenant to the 115 swinging pawl lever 83. That lever is engaged by the actuating cam 85 which is appurtenant to the registering pawl arm 59, and may, as herein shown, be combined with the locking arm 76. On account of the diverse directions of swing of the cam 85, and the lever 83, the end of the lever is preferably made ball shaped. As shown in Fig. 5, the cam path 86 of the cam 85 is inclined to the direction in which the cam swings to a sufficient extent to impart a suitable amplitude of movement to the pawl lever 83, whereby each swinging movement of the 120 125

registering pawl arm 59 in advancing the trip register dials, serves also through the cam 85 to advance the units dial of the totalizer one unit for each movement of advance of the trip register dials. Moreover, the path of the cam may be varied as may be desired, so as to advance the totalizer in any desired time or portion of the stroke of the registering mechanism.

10 The units ratchet 80 is preferably provided with an ordinary detent pawl 88 which engages with the peripheral teeth of the ratchet wheel to prevent it from turning backwardly in the ordinary operation of the machine. As a further feature of the interlocking mechanism to prevent the units dial, and hence the totalizer train from being turned forward or back, relative to the trip registering train, the ratchet wheel or some 15 portion of the units dial is provided with projecting stop teeth 90, which are herein shown to be coincident with the peripheral teeth, although in the present instance this coincidence is merely for convenience of manufacture. These teeth are controlled by a stop pawl 91 which is pivoted at 92 and is provided with two stop projections 93 and 94, which project outwardly into the circular pathway of the stop teeth 90, the distance between the two stop projections being such that one or the other of them is always 20 in that circular pathway; and the stop pawl 91 is moved back and forth with the swinging movements of the lever 83, so as to withdraw 25 the stop projections 93 and 94 alternately out of the circular path of the stop teeth 90, so as to allow the said teeth to pass alternately by the respective projections. As 30 a means for thus swinging the stop pawl 91 in proper relation to the pawl lever 83, the hub of the latter is made cam shaped and engages the pawl 91, which is preferably bifurcated as here shown and spans the cam-shaped hub 95 of the lever 83. Thus the 35 movements of the units dial are controlled by the operation of the stop pawl 91, the pawl lever 83, and the cam 85 appurtenant to the trip registering mechanism, thereby interlocking the trip and totalizer mechanisms so that neither one can be advanced by the registering mechanism without advancing the other. By this arrangement also the totalizer as well as the trip register remains 40 locked against all abnormal movement throughout the operation of the recording and the resetting mechanisms.

In connection with the functions of a recording fare register it is found desirable to make separate records of the different directions or zones in which the fares are registered, indicating upon the record itself in connection with each operation the direction or zone in which it was registered. In this connection also it is found desirable to pro-

vide means for automatically changing the 65 visible or transient direction indicator and its impressing devices so as to put it in position for indicating and recording the succeeding direction or zone, instead of relying upon the operator to make the change. In 70 the present invention means are provided for thus automatically changing the visible indicator and its recording type in connection with each recording operation. Interlocking means are also provided for, or as 75 associated with, the recording, direction indicating and resetting devices, whereby each is prevented from operating except in proper sequence.

Reference has already been made to the 80 direction dial 51 and its arm 52. That arm is mounted to turn upon the bushing 53 which also forms a bearing for the right hand end of the hundreds dial shaft 45. The face of the dial 51 is provided with suitable words or symbols as "In," "Out," "Down," "Up," etc., indicative of the directions in which the trips are being made, or they may have other words or symbols indicative of the zones into which the routes 85 of the car may be divided, this being frequently done on interurban or other extended lines. The zones are generally arranged to include the distance intended to be covered by a five cent fare. 95

The direction indicating arm 52 is preferably provided with a spring latch 101 which engages with suitably disposed notches 102, 103, of the casing, these notches being suited in number and position to the 100 different positions in which the dial is to be held. The latch 101 holds the arm and its dial yieldingly in these respective positions, leaving it free to be moved by a moderate effort from one position to the 105 other. As a means for thus moving the direction indicating dial automatically under the control of and in proper relation to the associated mechanism, the arm 52 is extended rearwardly and is provided with a cam-like 110 slot, the edges 104 of which engage with a pin or stud 105 mounted in the side of the gear 106, that gear being mounted to rotate upon the stud 107 appurtenant to the side of the case (see Figs. 6, 7 and 8). The contour of the edges 104 and the position and radius of movement of the stud 105 are suited to swing the direction arm 52 and its dial 51 to the positions in which they visibly indicate the desired directions or zones; and 115 these may be varied to suit different conditions. In the present instance, the two directions "out" and "in" are indicated and recorded. When the parts are in the position shown in Fig. 7, with the pin 105 at the 120 upper part of its movement, the dial is held in its downward position, but when the pin is at approximately the opposite or

lower side of its orbit, the dial is held in the other position, as indicated in Fig. 5. By a suitable arrangement of the slot, and pin, one or more additional or intermediate zones may be indicated.

As a convenient way of connecting the gear 106 with the recording devices, a gear 109 is mounted upon the shaft 110, and meshes with the gear 106, the ratio between these gears corresponding to the number of different zones or directions to be indicated. Hence in the machine herein shown, which is adapted to indicate two directions or zones, the diameter relation of the gear 106 to the gear 109 is 2 to 1, so that the gear 106 and its stud 105 will be turned half a revolution at each complete rotation of the gear 109. That gear is rotated during the recording operation by means of the recording or printing knob 112, which is on the outer side of the case and accessible to the conductor. The turning of this knob serves to operate the recording mechanism and to change the direction indicating mechanism, and also to inaugurate the operation of the interlocking mechanism.

In order to prevent the recording knob 112 from being turned in the wrong direction, the shaft 110 has fixed upon it the ratchet wheel 113, on which a small spring-pressed detent 114 operates to prevent backward movement. The ratchet wheel 113 is also utilized as a crank disk, carrying the crank stud 115, which is connected by means of the link 116 with the wrist plate or bell crank 117, which is mounted to swing upon the shaft 118. The bell crank is connected at 120 with the link 121, the other end of the link being connected at 122 with the recording or printing arm 123, which is pivotally mounted upon the shaft 124 and carries the recording strip holder. That holder is removable from the arm, provision being made for taking it out through a door in the end wall of the case, similar to the door shown for this purpose in U. S. Patent #567,315. The record strip 125 is carried upon the removable holder, comprising a disk-like plate 126, which is provided with suitable bosses for carrying the necessary shafts and spindles for supporting an extended record strip of paper or other suitable material. That strip is disposed in a coil 128 and passes over the anvil or platen 129, over which it is drawn by means of the geared rolls 130 and 131, and is rewound upon a frictionally driven spool 132. The rolls 130 and 131 and the frictionally driven spool 132 are connected by means of a train of gearing on the back of the plate 126, and are advanced by means of a ratchet wheel 135, appurtenant to that train of gearing. A spring detent pawl 136 is mounted upon the back of the plate 126 and engages with

the ratchet 135, holding the train of gears, 65 and hence the associated record strip against movement, with relation to the printer arm 123, as the latter is moved up to the recording position shown in Fig. 8. As the arm is swung back from the recording position 70 toward its lowermost position shown in Fig. 5 the teeth of the ratchet 135 collide with the advancing pawl 138 which is pivotally mounted upon the bracket 139, thus advancing the record strip, and thereby separating 75 the succeeding impressions far enough to make them easily readable. This removable record holder and its operating mechanism are shown, described and claimed in another co-pending application; and hence are not 80 described herein in minute detail. By the description thus far given of these devices it will be seen that that portion of the record strip 125 which rests upon the platen 129 is pressed up against the row of impressing 85 type which are at the recording position designated by the dot-and-dash line 3, whenever it is desired to record the number of fares and the direction visibly indicated upon the register dials at the conclusion of 90 each trip or zone, the rising and falling movement of the arm 123 being communicated from the external knob 112 through the intervening bell crank mechanism already described. 95

Means operating with the general interlocking mechanism are provided for locking the recording mechanism at the conclusion of its operation so as to prevent the repetition of that operation until the interlocking 100 devices have in due course been again set to their clear position, which can only be done when the registering dials are at their zero position, thereby insuring the return of these dials to zero if they are not already 105 there during the recording operation. The disk 113, which also serves as a ratchet wheel, is provided with a recess 142 in its side, that recess being adapted to receive a projection 143 of the locking pawl 144. 110 That pawl is pivoted at 145 to the inside of the casing; and the upper end is yieldingly held toward the recess 142 by means of a spring 146. The lower end of the locking pawl is operated and controlled by means 115 of the interlocking mechanism appurtenant to the interlocking shaft 150. An arm 151 upon that shaft engages with the inclined surface 152 and moves the pawl 144 out of locking relation to the ratchet disk 113 of 120 the recording mechanism, when the parts are in the position shown in Figs. 2, 4 and 5, in which the dials are in zero position. When thus unlocked, as shown in Fig. 2, the recording mechanism is again released for 125 the succeeding operation, subject only to the control of the registering mechanism, through the arm 76 and the latch arm 77,

which prevent the operation of the recording mechanism, except when the registering arm 59 is in the position shown in Figs. 2, 4 and 5.

5 The devices directly concerned in the resetting mechanism will now be described:—

The resetting yoke 180 is mounted at its ends to swing in a concentric relation to the

10 trip register dials, the general form of yoke and the manner of mounting it being similar to that shown in the aforesaid Patent 567,315 that yoke being provided with an external lever 181, by means of which the yoke is swung forward and back by the operator to an angular extent substantially equaling the angular spacing of the teeth of the dial ratchet wheels 34, 35 and 36. The yoke 180 is provided with a shaft 182 upon which the resetting pawls 183 and 184 and 15 185 are independently mounted and are pressed into engagement with their respective ratchets 34, 35 and 36, by means of springs 186. Each of those ratchets is provided with a pawl support 188, which is so 20 disposed upon the ratchet as to engage with the respective resetting pawls and hold them out of advancing relation to the respective dials as shown by the position of the tens pawl 184 in Figs. 12 and 13, when the dial 25 is at its zero position, and the resetting yoke is in its rearward position shown in Fig. 12. Thus as each dial is stopped at its zero position by means of its stop finger, or 30 its associated stop key 168, the resetting pawl for that dial is held out of advancing relation to the teeth of the ratchet so as to permit the yoke to swing forward, carrying with it the dials which are not yet restored to zero position, the pawls of which are still 35 free to drop behind the teeth of their respective ratchets as shown by the pawl 184 in Fig. 9, and pawl 183, Fig. 12. Thus the resetting yoke is enabled to continue its forward and back movements without being arrested by the dials which have arrived 40 at zero position, and until all of the dials are brought to zero position, at which time the resetting yoke is stopped in its forward position as shown in Fig. 14 by the dropping 45 of the interlocking arm 74.

The pawl supports 188 are herein shown to be appurtenant to the ratchet wheels, and in form and effect constitute an extension of one of the teeth of the ratchet. 50 Therefore in this construction, the registering pawls 55, 56 and 57 are made narrow as shown by the dot-and-dash outline of the end of the pawl 56 in Fig. 11; or the end of that pawl is cut away to clear the end of 55 the support 188 similar to the way in which the detent 62 is shown to be cut away in Figs. 9 and 10, to clear the support 188. This construction and arrangement of the pawl support is, however, merely an inci-

60 dent. Obviously, the support may be placed at some other position of the ratchet or upon the dial itself at one side of the plane of the ratchet wheel, the resetting pawl being suitably extended, so as to rest upon the support and be held out of advancing relation to the ratchet teeth when the dial comes to its zero position.

65 Each of the ratchet wheels 34, 35 and 36 of the trip register dials is provided with a notch 155, which, when the dials are at their zero indicating position, stand at the position shown in Fig. 12, the upper sides of these stop notches forming forwardly facing stop shoulders 156 for engaging with the upper ends of the stop pawls 157, 158 and 159, respectively. These fingers are rigidly connected to a stop arm 160 which is secured to the interlocking shaft 150. That shaft is also provided with a latch arm 162 which extends upwardly in engaging relation to the latch 163 which is loosely mounted on the shaft 118 and is held downwardly toward latching engagement with the arm 162 by means of the spring 164, the other end of which is attached to the arm 162. 70 While the trip register dials are at zero, and during the continuance of the registering operations, the latch 163 is in latching engagement with the arm 162, thus holding the interlocking shaft 150 and its appurtenances 75 in the position shown in Figs. 2, 4 and 5, and thereby holding the stop fingers 157, 158 and 159 away from the dials as shown in Fig. 4. In this position of the shaft 150 the locking lever 74 is held in its uppermost position, shown in Fig. 4, thereby locking the resetting mechanism out of operation. But when the latch arm 162 is released from the latch 163 at the beginning 80 of the recording operation, the spring 165, bearing upwardly against the latch arm 162 swings that shaft forward, thereby carrying the stop fingers 157, 158 and 159 yieldingly against the faces of the ratchets 34, 35 and 36. If it should happen that all of the registering dials are then at the zero position, the stop fingers will enter the notches 155 of all the ratchets, as shown in Fig. 14, and 85 allow the locking arm 74 to drop at once to the position shown in Fig. 14. But if any of the dials are not at the zero position, the notches 155 will be away from the stop fingers for those dials, and the fingers will 90 therefore rest against the faces of the teeth as shown in Fig. 9, thereby holding the shaft 150 and its appurtenances in a position intermediate those of Figs. 4 and 14. In order to enable the stop fingers while 95 supported in this position by one or more of the dials to positively stop such other dials as may arrive at the zero position, each of the fingers is provided with a stop key 168 pivotally mounted upon the finger, and 100 105 110 115 120 125

yieldingly held by the spring 169 toward the position shown in Fig. 12, the key being provided with a stop shoulder 170, which prevents further inward movement of the 5 key relative to the finger. Thus the series of stop fingers and the stop arm 74 are supported in the position shown in Fig. 9 by the ratchets of those dials which are away from zero position, the key 168 being also supported in the position shown in that figure. Thus while any of the dials remain out of 10 their zero position, the stop fingers being rigidly connected would not of themselves serve to stop the dials which arrive at zero; 15 but the keys 168 being free to move, are carried by their springs into the notches 155 as the dials arrive at zero position, as shown in Fig. 12. When all of the dials have arrived at zero position so as to bring all the 20 notches 155 into register with the stop fingers, the latter drop into those notches as shown in Fig. 14, thereby allowing the locking arm 74 to drop to the position shown in that figure, at which position it stops further movement of the resetting devices; and 25 also releases the interlocking mechanism from the safety pawl 172. That pawl is pivoted at 173 to the side of the case and is held in the middle of its range of swing by 30 means of the spring 174. The end of the interlocking arm 74, and the adjacent portion of the resetting yoke 180 are so shaped and adapted to each other's movements that the 35 arm 74 locks the resetting arm in its forward position against backward movement when the parts are in the position shown in Fig. 4, during the registering operations, and also during the impressing portion of the recording operation. When the latching 40 arm 162 is released from the latch 163 at or near the conclusion of the recording operation as above described, the interlocking lever 74 falls to the position shown in Fig. 9, being supported in that position by one 45 or more of the stop fingers 158 or 159, resting against the dials which are out of the zero position, and while in this position the resetting yoke is free to swing forward and back. As the arm 74 thus drops to the 50 position shown in Fig. 9, it turns the pawl 172 downwardly, the arm 74 being provided with a shoulder 175 which collides with the pawl 172, if any attempt is made to push upwardly on the push button 176 to throw off 55 the interlocking mechanism before the resetting operation is complete. But when the dials have all arrived at their zero positions so as to let the mechanism down to the position shown in Fig. 14, the end of the arm 60 74 drops out of contact with the pawl 172, thereby enabling that pawl to swing to its middle position shown in that figure, from which it readily swings upwardly as the arm 74 is lifted by the push button 176.

In this lowest position of the arm 74, its 65 projection 177 drops behind a projection 178 of the resetting yoke 180. Thus the interlocking arm 74 serves also to stop the further operation of the resetting devices when the dials are at zero as shown at Fig. 14. 70

In construction, function and mode of operation, the arm 74, the pawl 172 and the resetting yoke 180, relevant to their interlocking features, are substantially like the corresponding parts shown and described in 75 the aforesaid Patent 567,315, and are shown and described herein only for the purpose of making clear their interrelation with the other features of the machine.

In order to move the interlocking mechanism positively away from its latched position, shown in Figs. 2 and 7, when the latch arm 162 is released by the latch 163, the bell crank 117 is provided with a cam arm 161, the end of which is turned inwardly behind 85 the side projection 166 of the latch arm 162, the inclined or cam-like surface 167 tending to force the arm 162 forwardly as shown in Fig. 8, so as to carry the shaft 150 and its appurtenant members positively to the position shown in Figs. 8 and 12, in case the 90 spring 165 should fail to overcome the frictional or other resistance of the parts, thereby positively moving the interlocking devices into this stage of their operation, at 95 the proper and predetermined stage in the operation of the recording mechanism.

In Figs. 16, 17, 18 and 19 is shown an auxiliary or extension of the interlocking system, to prevent improper operation of 100 the machine. This particular device is for the purpose of preventing a possible displacement of the recording type wheels associated with the register dials, so as to prevent the type from being partly out of line, 105 when taking the impression record. In this instance the device is employed as an adjunct to a common form of full stroke mechanism, the well-known function of which is to compel the registering arm to make a full 110 stroke in each direction. The well-known portion of this mechanism consists of a rack 190, appurtenant to the case, and a pawl 191 pivotally mounted upon the registering arm or yoke 59, the pawl when free 115 from the rack being held in a middle position shown in Figs. 4 and 18, by means of the spring 192, the pawl being swung to the right from this middle position when the arm 59 is moved to the left as shown in Fig. 120 17, and in the opposite direction when the arm is moved to the right, as shown in Fig. 19. The pawl does not become effective to prevent backward movement until it catches into the first tooth of the rack as shown in 125 Fig. 17. By comparison of the extreme forward position of the arm 59 shown in Fig. 4, with the position shown in Fig. 17, it will

be seen that the arm 59 is free from the control of the pawl 191 during a very considerable angle of movement at the first part of its stroke, on account of the clearance required between the end of the pawl and the rack teeth, to enable the pawl thus to be reversed. This permits of moving the registering arm and its associated recording wheel forward to this extent, and then 10 gently letting the registering arm backwardly to the position shown in Fig. 4; and it has been found that frictional or other causes will sometimes hold the dial at its advanced position with the impressing type 15 cut of their recording position, while still enabling the registering arm 59 and its associated interlocking devices to move back to the positions of Figs. 4 and 5, at which position the recording mechanism is free to be 20 operated; and if operated under such circumstances would produce either an incorrect or at least doubtful record. The object of this particular feature of the present invention is to provide for locking the registering arm at an earlier position in its forward movement than is possible with the known full stroke devices.

The arm stop pawl 195 is pivotally mounted at 196 upon the casing; and is provided with a spring 197 which operates to press the upper end of the pawl toward the registering arm 59. The pawl is provided with a notch or shoulder 198, which engages with a shoulder 199 appurtenant to the registering arm 59 at the position shown in Fig. 16, thus preventing return movement of the arm 59 until it has made its complete backward stroke. In order to swing the arm stop 195 out of the way, to permit the full 40 backward movement of the arm 59, the pawl 191 is provided with a member 200 which as the pawl swings toward the right from the position shown in Fig. 18, engages with the face 201 of the arm stop, and moves it 45 backwardly to the position shown in Fig. 19, thereby preventing the shoulders 198 and 199 from engaging with each other. After the upper end of the pawl 191 passes the last tooth of the rack, it swings downwardly to 50 the position shown in Fig. 18, thus allowing the arm stop 195 to again swing forward to the position shown in Fig. 4, ready for the next forward movement of the arm.

In the machine of the aforesaid Patent 55 567,315, the bell is operated directly from the units ratchet of the trip registering train, through the interposition of the resetting pawl for the units dial. In the present machine the bell is operated directly by the 60 registering arm, and is thus independent of the units ratchet, being thus locked out of operation during the time that the registering mechanism is locked out of operation. The bell shaft arm 25 is provided with a

finger 205, which is pivotally mounted at 65 206 upon the arm, and is provided with a spring 207, which presses the finger outwardly, the finger and the arm being provided with stop shoulders 208 and 209 which stop the finger at the position shown in Fig. 70 4. The lower end of the arm 59 is provided with a bell operating member 212, which swings forward and back with the arm. That member is provided with a toe 213, which engages with a shoulder 214 of the 75 finger 205, thereby retracting the pawl hammer 24 from the bell, until the parts reach the position shown in Fig. 18, at which time the heel 215 of the member 212 by its swinging movement depress the finger 205 and releases it from the toe 213, thereby releasing the bell hammer which is then carried against the bell by means of the spring 26. As the registering arm 59 and its bell operating member 212 swing forward toward the 80 85 position shown in Figs. 4 and 14, the finger 205 is wiped downwardly by the end of the member 212, thus permitting it to pass, after which the finger 215 again swings up into the pathway of the member 212, ready for 90 the succeeding operation.

In the very rapid or jerky operation to which these registering machines are sometimes liable, it is found that the dials have a tendency to overrun their proper stopping 95 positions. To overcome this difficulty, I have provided the dial stop, best shown in Figs. 1, 5 and 18. This stop consists of a member 65, pivotally mounted at its ends in brackets appurtenant to the case 20, and 100 provided with integral fingers 66, which are disposed in the pathway of the dial ratchets 34, 35 and 36, the swinging movement of the stop member 65 enabling these fingers to be swung in front of the inclined faces of 105 the ratchet teeth, as shown in Fig. 18, or out of that pathway as shown in Fig. 5. The stop member is provided with the spring 67, the tendency of which is to press the stop fingers toward the dials to the position 110 shown in Fig. 18, the stop fingers being carried outwardly against the pressure of the spring by the registering arm 59, which as it moves to its backward resting position collides with the fingers, and swings them outwardly away from the ratchet wheels far enough so that the registering arm upon 115 this forward movement carries the successive ratchet teeth forward far enough to clear the points of the fingers 66, thus allowing the latter to swing back into the pathway of the succeeding teeth, engaging the forwardly inclined portions thereof, and stopping the ratchets at the end of their 120 registering movement, thereby preventing 125 them from being carried beyond that position by their momentum, or otherwise.

In the type of dial advancing mechanism

shown herein, the registering pawls 55, 56 and 57 are disposed at different distances from the axial centers of the dials as best shown in Fig. 4, the units and tens dials being provided with correspondingly deepened notches at the respective points where these pawls rest in advancing the succeeding dial of the train. The units dial 34 is thus provided with a deeper notch 37 than the other dials; and in order to prevent the stop finger 157 or its stop key 168 from dropping down into the notch 37 while this portion of the dial 34 is passing the finger, the latter is provided with a projection 38 which rests upon the top of the preceding tooth 39, as shown in Fig. 15, until the upper end of the finger and key are safely across the notch, thereby preventing either of them from dropping into the deep notch 37 and possibly stopping the dial 34 at the wrong position.

The complete and consecutive operation of this machine is as follows:—The interlocking mechanism is assumed to be in its backward or clear position shown in Figs. 2, 4 and 5. In this position only the resetting devices are locked out of operation, the registering and recording mechanism being left free for action. The registrations are effected by means of the lever 60, thereby advancing the trip register dials and the total register dials coincidentally, one unit at each actuation. At the end of each trip or zone, the recording mechanism is operated by turning the knob 112 one complete rotation. During the first part of this rotation the latch 77 is swung under the locking arm 76, thus locking the trip and total mechanisms and the bell mechanism out of operation. The continued rotation of the knob 112 raises the printing arm and impresses the record strip 125 against the line of type, which are at the recording position, over the platen 129, thus making a permanent record of the number shown upon the trip dials, and also the direction or trip shown on the direction dial 51. During this upward movement of the printer arm 123, the devices which serve to advance the recording strip are held against movement by the detent pawl 136. As the rotation of the knob 112 continues, the printer arm 123 is moved downwardly again, away from the type, thus bringing the ratchet wheel 135 against the advancing pawl 138, and thereby advancing the record strip one space. After the record has been impressed upon the strip, the continued rotation of the knob 112 swings the latch 163 upwardly from in front of the latch arm 162, thereby releasing the latter and allowing it and its shaft 150 to be carried by the spring 165 to the position shown in Figs. 9 and 12. If the shaft 150 or any of its appurtenances should by means of

friction or otherwise remain in latched position after being released by the latch 163, the continued movement of the arm 161 carries the inclined face 167 of that arm against the projection 163 of the latch arm 162, thereby moving the interlocking mechanism 65 positively to its proper place. During the latter portion of the rotation of the knob 112 and after the making of the record impression, the revolving stud 105 operates upon the cam surfaces 104 of the direction 70 arm 52 and moves that arm to its succeeding position, at which it designates the succeeding direction or zone to be recorded. Upon the completion of a single rotation of the knob 112, it is locked against further movement for the present, by means of the pawl 144, the projection 143 of which enters the recess 142, in the side of the gear disk 113, that disk remaining thus locked until the trip register dials have been reset to zero 80 and the interlocking mechanism restored to the position shown in Figs. 2, 4 and 5.

If no fares have been registered during the trip or zone, the interlocking mechanism will, upon being released from the latch 163, 85 drop at once to the position shown in Fig. 14, on account of the fact that the registering dials are already at zero position. In that case it is only necessary to push upwardly on the push knob 176, which projects 90 through the bottom of the case for that purpose, thereby carrying the interlocking mechanism back to the position shown in Figs. 2, 4 and 5. If, however, some fares have been registered during the trip, one or 95 more of the dials will hold the stop fingers and the interlocking arm 74 at the position shown in Figs. 9 and 12, in which position the resetting yoke is released; and is then operated by means of the projecting lever 100 181 on the outside of the case. That lever is moved back and forth until the last of the dials has been brought to zero position, at which time the stop fingers and the interlocking arm 74 drop to the position shown 105 in Fig. 14, thus locking the resetting yoke 110 180 in its forward position, thus indicating to the sense of touch of the operator that the resetting operation is completed. The next step is to push the push button 176 upwardly, thereby carrying the interlocking mechanism to the position shown in Figs. 2, 4 and 5, in which position it is caught and held by the latch 163, the latching movement carrying the upper end of the latch arm 77 115 out from beneath the locking arm 76 of the registering mechanism, thereby releasing that mechanism. The returning movement of the interlocking mechanism to the positions shown in Figs. 2, 4 and 5 carries the 120 arm 151 downwardly to the position best shown in Fig. 2, thereby withdrawing the upper end of the locking pawl 144 out of

engagement with the gear disk 113, and thereby releasing the recording mechanism. The upward movement of the arm 74 also serves as best shown in Fig. 2 to withdraw 5 the locking member 70 from in front of the registering lever 60, thus leaving it free to be operated.

It is generally desirable to impress upon the record strip the number of the car or the 10 number of the register in which the record was taken. This may be done as shown in the aforesaid Patent 567,815, by providing a separate column on the record strip for the register or the car number. But this involves 15 the useless repetition of the number and also involves the use of an additional column, which by the arrangement herein is rendered unnecessary. All practical purposes are served by substituting the number 20 of the register for one of the directions or zones, as shown by the record strip in Fig. 1, in which the number 1329 of the register is substituted for the direction word or symbol "Out." Where this is the understood 25 practice, it leads to no misunderstanding; and is sufficient for all practical purposes.

It is not necessary to have more than two direction indicating positions of the dial 51, even when applied to the zone system. For example, with the machine as herein shown, which is adapted to indicate only the 30 directions "in" and "out", it is entirely feasible to make an intelligible record of fares registered in a large number of zones. Assuming for example that the route is divided into five zones. In the outward trip, while registering and recording the fares in the first zone, the direction dial stands in 35 the "out" position. Then after the recording operation for that zone, the recording operation is repeated, which impresses the "in" direction upon the record strip, accompanied by ciphers in the fares column. 40 This operation serves to restore the dial to its "out" position, where it remains during the registering and recording of the fares in the second outward zone, after which the recording operation is repeated with the zero indication so as to again restore the 45 direction dial to the out position for the third zone, and so on. At the end of the fifth zone, which is here assumed to be the end of the outward trip, the dummy recording operation is not thus repeated but during 50 the first inward zone the dials are left in the in position given to them by the recording of the fifth outward zone, the impressions of the succeeding records of the inward zones being similarly separated by dummy or zero impressions with the dial at the out position. The resultant record will 55 show the consecutive record of the outward and inward zones in their proper order, but

separated by the zero or dummy impressions. Although this procedure makes the record strip somewhat longer than it would otherwise be, the extra length is amply provided for by the arrangement for carrying a long record strip. 65

The terms "in", "out", "up", "down", "forward", "backward" and other terms indicative of direction and position are herein employed in their relative and not their absolute sense, it being understood that 70 these directions may be changed, reversed, inverted or transposed in many ways that will be obvious to the mechanic or designer.

In a co-pending application filed by me November 28th, 1905, Ser. No. 289,387, 80 which was issued on December 21st, 1909 as Patent No. 944,242, I have shown, described and claimed the totalizer devices which are shown in Figs. 2, 20 and 21 of this application. They are shown and described here- 85 in for the purpose of claiming them or relevant portions of them in combination with the other mechanism of a fare register with which they are here shown to be in operation. In another co-pending application, 90 Ser. No. 295,331, filed January 10th, 1906, which was issued on April 8th, 1913, as Patent No. 1,058,312, I have shown, described and claimed the removable record strip carrier and feeder, which is shown in Figs. 1 95 and 5 of this application.

I claim as my invention:—

1. The combination in a registering machine, of registering and resetting mechanism, an external registering lever for operating the registering mechanism, interlocking devices between the said mechanisms, and a locking bolt operated by the interlocking devices, and mounted to swing into and out of the path of movement of the said 100 external lever, whereby that lever is directly locked throughout the operation of the resetting mechanism.

2. The combination with registering and resetting mechanism, of an external lever 110 serving as a prime mover for operating the registering mechanism, interlocking devices between the said mechanisms, a locking device mounted to swing into and out of the pathway of the registering lever, and operatively connected with and controlled by the interlocking devices, whereby the said prime mover is locked prior to the operation of the resetting mechanism and is unlocked at the 115 end of that operation.

3. The combination with registering and recording mechanism, of an external prime moving lever for operating the registering mechanism, a locking device mounted to move into and out of the path of movement 125 of the lever, and means connected with and controlled by the recording mechanism for moving the locking bolt to its locking posi-

tion in the path of movement of the said lever at the beginning of the recording operation.

4. The combination with incased registering, recording and resetting mechanisms, of an external prime moving lever for operating the registering mechanism, a locking device mounted for movement into and out of the pathway of the lever, and means controlled by the movements of the recording and resetting mechanisms for moving the locking device into the pathway of the said lever to lock the registering mechanism out of operation, and allowing the said lever to be released at the completion of the resetting operation.

5. The combination with registering, recording and resetting mechanism, of an external operating lever for the registering mechanism, a locking member mounted for movement into and out of the pathway of the said lever, and interlocking devices operating under the joint control of the recording and resetting mechanisms for moving the locking member, whereby the said operating lever is locked externally of the case at the beginning of the recording operation, and is released from the said control at the end of the resetting operation to allow the lever to be unlocked.

6. In a registering machine, the combination with trip and totalizer registering mechanisms, of an arm for actuating one of said mechanisms, and a cam movable with the other of said mechanisms engaging and operating the said arm.

7. In a registering machine, the combination with trip and totalizer registering mechanisms, of a pawl arm for advancing the totalizer dials, and a cam appurtenant to the trip mechanism, and operating the arm in predetermined relation to the movements of the registering mechanism.

8. In a registering machine, the combination with the trip and totalizer registering mechanisms thereof, of an advanceable member operatively connected with the totalizer train and provided with stop teeth, a stop pawl having projections mounted to swing into and out of the pathway of the teeth of the advanceable member, and arranged to have one or the other of the said projections at all times in the said pathway, means for advancing the said member, means for moving the stop pawl to carry its teeth alternately out of the pathway of the teeth of the advancing member, and a cam movable with the trip registering mechanism for actuating the totalizer and its stop device.

9. In a registering machine, the combination of a registering train provided with a series of stop teeth, a stop pawl provided with stop projections mounted to swing into and out of the pathway of the stop teeth,

means for advancing the said registering machine, provided with means for moving the stop pawl to carry its projections alternately out of the pathway of the stop teeth, and a cam for operating the said advancing means.

10. In a registering machine, the combination with the trip and totalizer mechanisms, of means for operatively connecting the two mechanisms, and preventing them from getting out of register with each other, including a series of stop teeth movable with the totalizer mechanism, a stop pawl provided with projections and mounted to swing into and out of the pathway of the stop teeth, means for advancing the totalizer train and operating the stop pawl, and a cam moving with the trip mechanism for operating the totalizer advancing means.

11. In a fare register, in combination with a dial for transiently indicating different trip directions or zones, means for making a consecutive record of the directions or zones thus indicated, and means operable by the recording means for changing the dial indication in connection with each recording operation.

12. In a fare register, in combination with a dial for transiently indicating different directions or zones, and arranged to be moved to positions representing the respective directions or zones separately, means for making a consecutive record of the directions or zones thus transiently indicated, and means operable with the recording means for moving the dial at each recording operation to indicate the next direction or zone.

13. In a fare register, in combination with a dial for transiently indicating different directions or zones, dials for transiently indicating the fares registered in each direction or zone, means for making a consecutive record of the fares thus registered in each direction or zone, and an associated record of the direction or zone in which they were registered; and means operable with each recording operation for changing the dial indication to indicate the succeeding direction or zone.

14. In a fare register, in combination with a dial for transiently indicating different directions or zones, and arranged to be moved to positions separately indicating the respective directions or zones, dials for transiently indicating the fares registered in each direction or zone, means for making a consecutive record of the fares thus registered, and for making an associated record of the direction or zone in which the recorded fares were registered, and means operable by the said recording means for moving the direction indicating dial to the position indicative of the succeeding direction or zone.

15. In a fare register, in combination with

a movable dial for transiently indicating different trip directions or zones, means for making a consecutive record of the directions or zones thus indicated, and means operable with and at the conclusion of the recording operation for changing the dial indication to indicate the succeeding direction or zone.

16. In a fare register, the combination

10 with devices for making a record of the fares registered, a revolute member for actuating the recording device, and a locking member controlled by associated devices of the machine for unlocking the said revolute member after each complete actuation of the recording device.

17. In a fare register, in combination with devices for making a record of the fares registered, resetting devices for re-

20 turning the registering dials to their zero position, a revolute member for actuating the recording device, and locking means controlled by the resetting devices for unlocking the said revolute member after each com-

25 plete actuation of the recording device.

18. In a fare register, the combination of registering dials, means for making a record of the fares registered by the dials, resetting devices for moving the dials to their 30 zero positions, a revolute member for actuating the recording devices, and a locking member controlled by the position and movements of the resetting devices for locking the revolute member at the end of each 35 complete actuation of the recording devices, and during the resetting operation.

19. In a fare register, the combination of dials for registering the fares, means for transiently indicating the different directions 40 or zones in which the fares are registered, means for making a record of the successive directions or zones, and for making an associated record of the fares registered in each direction or zone, a revolute member for 45 actuating the recording means and for changing the direction indicating means to indicate the next direction or zone, resetting devices for returning the registering dials to their zero positions, and locking means controlled by the resetting devices for locking 50 the said revolute member while the resetting devices are in operative position, and for unlocking that member when the resetting devices are out of operative position.

55 20. In a recording fare register, the combination of dials for registering fares and for transiently indicating different directions or zones in which the fares are registered, recording devices for making a consecutive record of the successive directions 60 or zones, and of the fares registered in each direction or zone, a revolute member for actuating the recording devices, and for moving the direction dial to indicate differ-

ent directions or zones, resetting devices for 65 moving the registering dials to their zero positions, means, released by the recording devices for holding the resetting devices out of operation, means for locking the revolute member when the resetting devices are 70 in operative position, and for unlocking the said member when the resetting devices are out of operative position.

21. In a recording fare register, the combination of a dial for transiently indicating 75 different trip directions or zones, recording devices for making a consecutive record of the successive directions or zones indicated by the dial, a revolute member for actuating the recording devices, and means 80 operable by the revolute member for changing the dial indication at each recording operation.

22. In a recording fare register, the combination with a dial for transiently indicating 85 different trip directions or zones, recording devices for making a consecutive record of the directions or zones indicated by the dial, a revolute member for actuating the recording devices, a second revolute member 90 for changing the dial indication, and gearing connecting the two revolute members whereby the number of revolutions of the first revolute member is an even multiple of the number of revolutions of the second revolute member.

23. In a recording fare register, the combination of recording devices, resetting devices for turning the register to zero, interlocking devices for locking the resetting devices out of operative position, and means 100 operable by the recording devices for releasing the interlocking devices and moving them positively to release the resetting mechanism.

24. In a recording fare register, the combination of registering dials, recording mechanism for making a consecutive record of the succeeding dial registrations, resetting mechanism for moving the dials to their 110 zero positions, interlocking devices between the recording and resetting mechanisms, means for holding the said interlocking devices in position to prevent the resetting operation during the recording operation, and means operable with the recording mechanism for releasing the said interlocking mechanism, and moving it positively to release the resetting mechanism.

25. In a recording fare register, the combination of recording mechanism, resetting devices for turning the register to zero, and interlocking devices between the resetting and recording devices, comprising a locking arm for the recording devices, stop 120 pawls for stopping the register dials at zero, and means controlled by the said pawls 125 when the dials are at zero for locking the re-

setting devices out of operation, and unlocking the recording devices.

26. In a recording fare register, the combination with registering dials, recording mechanism for making a consecutive record of the succeeding dial registrations, resetting devices for moving the dials to their zero positions, and interlocking mechanism between the resetting devices and the recording mechanism, comprising a locking member for the recording mechanism, a locking arm for the resetting mechanism, and stop pawls controlled by the position of the dials, for locking the recording mechanism and unlocking the resetting mechanism when the dials are not at zero, and for locking the resetting devices and unlocking the recording mechanism when the dials are at their zero positions.
27. In a registering machine, the combination with the registering mechanism, of bell mechanism including an arm, a finger mounted for swinging movement on the said arm, a member movable with the registering mechanism, provided with a toe portion for engaging with the said finger, and with a heel portion for engaging with the finger to release the latter at the end of the desired movement.
28. In a registering machine, the combination with the registering mechanism thereof, bell operating mechanism comprising an arm appurtenant to the bell hammer, a finger mounted for swinging movement upon the said arm, a member appurtenant to the registering mechanism and mounted for swinging movement in a direction approximately at right angles to the swinging movement of the finger, the said member being provided with a toe portion for engaging with the said finger to retract the bell hammer, and with a heel portion for engaging the said finger to release the finger from the toe portion at the end of the retracting movement.
29. In a registering machine, the combination with the registering mechanism thereof, bell operating mechanism comprising an arm appurtenant to the bell hammer, a finger mounted for swinging movement upon the said arm, a member appurtenant to the registering mechanism and mounted for swinging movement in a direction approximately at right angles to the swinging movement of the finger, the said member being provided with a toe portion for engaging with the said finger to retract the bell hammer, and with a heel portion for engaging the said finger to release the finger from the toe portion at the end of the retracting movement, and means for resiliently holding the finger against the end of the register member.
30. In a registering machine, in combination with the registering mechanism thereof,

bell hammer operating devices including an arm appurtenant to the bell hammer and mounted for swinging movement, a finger mounted for swinging movement upon the arm, in a direction substantially at right angles to the direction of swing of the arm, a register member appurtenant to the registering mechanism mounted for swinging movement in a direction approximately parallel with the swinging movement of the arm, and provided with a toe for engaging with one portion of the finger to retract the bell hammer, and provided also with a heel for engaging with another portion of the finger to detach the latter from the toe portion at the end of the retracting movement of the bell hammer, and means for resiliently holding the swinging finger against the register member.

31. In a fare-recorder, the combination with a set of printing-counters denoting the number of fares recorded, of a type-wheel denoting the direction, impression devices for taking statements or records from said printing counters and said type-wheel, and means connecting the direction type-wheel and the impression devices by which said direction type-wheel is moved each time an impression is taken.

32. In a fare-recorder, the combination with a set of printing-counters denoting the number of fares recorded, of a type-wheel denoting the direction, a tablet or dial for indicating the direction, impression devices for taking statements from said printing-counters and type-wheel, and means for simultaneously moving the direction-indicator, the type-wheel denoting the direction, and the said impression devices.

33. In a fare-recorder, the combination with printing-counters denoting the fares registered, of a direction-printer mounted in line with said fare-printing counters, a direction-indicator, a platen or impression-bar, and connections between said impression-bar or platen, and the direction-printer and the direction-indicator, whereby upon each operation of taking a statement or record from the printing-counters and the direction-printer, the direction-printer and the direction-indicator are simultaneously set.

34. A direction-printer, an indicator, means for taking a print or impression from said direction-printer, said means controlling the positions of the direction-printer and the indicator.

35. A fare-printing counter, a direction-printer, and means for taking a print or impression from said fare-printing counter and direction-printer, said means controlling the position of the direction-printer.

36. A fare-printing counter, a direction-printer, means for taking prints or impressions from said fare-printing counter and

said direction-printer, and means connecting said direction-printer with said means for taking said prints or impressions, whereby the direction-printer is controlled by said means for taking the prints or impressions.

37. A fare-printing counter, a direction-printer, an indicator, and means for taking an impression from said printing-counter and controlling the shifting operation of the direction-printer and the indicator.

38. A fare-printing counter, a direction-printer, a direction-indicator, and means for taking impressions from said fare-printing

counter and said direction-printer, said means controlling the shifting operation of the direction-printer and the direction-indicator.

In testimony whereof I have signed my name to this specification, in the presence of two subscribing witnesses, this 17th day of January, 1906.

CHARLES F. LITTLEJOHN.

Witnesses:

ALFRED N. WHEELER,
MARTHA W. CORNWALL.
